No. 818,576.

PATENTED APR. 24, 1906.

G. B. SULLIVAN.

CAR LEVER.

APPLICATION FILED OCT. 26, 1905.

UNITED STATES PATENT OFFICE.

GEORGE B. SULLIVAN, OF EVANSTON, OHIO.

CAR-LEVER.

No. 818,576.

Specification of Letters Patent.

Patented April 24, 1906.

Application filed October 25, 1905. Serial No. 284,269.

To all whom it may concern:

Be it known that I, GEORGE B. SULLIVAN, a citizen of the United States, residing at Evanston, in the county of Hamilton and State of Ohio, have invented certain new and useful Improvements in Car-Moving Levers; and I do declare the following to be a clear, full, and exact description thereof, attention being called to the accompanying drawings, with the reference characters marked thereon, which form also a part of this specification.

This invention relates to certain new and useful improvements in hand-manipulated implements for moving vehicles traveling on track-rails, more particularly railway-cars, the movement being intended to be over limited distances only.

Devices of this kind are known as car-levers, car-movers, pinch-bars, &c., and for use they are supported on the rail close to a car-wheel and manipulated in a manner to act against the face of such wheel so as to rotate the same a limited distance, the resulting advance being followed up with the implement and by a similar manipulation of it, which is successively repeated until the car has been moved to the desired position. In order to carry out the intended operation, it is necessary that the implement rest firmly upon the rail while acting against the car-wheel.

One feature of my present invention relates particularly to means provided to secure this desired hold of the implement upon the rail.

Other features relate to improvements of the construction in general and in detail.

In the following specification and particularly pointed out in the claims at the end thereof is found a full description of my invention, together with its manner of use, parts, and construction, which latter is also illustrated in the accompanying drawings, in

which—

Figure 1 shows the implement and the manner of use, for which purpose parts of a car near one of its ends are shown, the position of the implement being the one at the beginning of its manipulation. Fig. 2 is part of a similar view, but at enlarged scale shows the implement in position after a manipulation, the previous position of the car-wheel, before moved, being shown in dotted lines. Fig. 3 is a top view of the implement as shown in the preceding figure. Fig. 4 is

an under side view of the same. Fig. 5 is an enlarged cross-section on lines 5 5 of Fig. 2. Fig. 6 shows the front end of the implement as it appears in Figs. 2 or 3 with a certain part removed.

The implement represents substantially a lever, fulcrumed at A, manipulated at B, and acting against the face c of a car-wheel C at D. The manipulation consists of bearing down at B to move the lever from the position shown in Fig. 1 to the one shown in Fig. 2, whereby point D is raised, thus acting against the car-wheel and shoving the same ahead, as shown by the two positions indicated in Fig. 2. The lever is now raised again, end D is shoved forward into the space under the wheel and between the rail below, as shown in Fig. 1, and the same manipulation is repeated. Generally the car when once started can be readily kept going by rapidly following up with the implement behind the wheel.

As to construction, the implement consists of the handle 8, which is of wood, and of the lever 9 proper, which is of metal, preferably malleable iron or cast-steel. The wooden handle is merely a continuation of this iron lever in one direction, and both may also be in one integral piece. At one end the metal part has a socket 10 to receive one end of the wooden handle 8. Otherwise and forward of this socket lever 9 is substantially of T-shaped profile, consisting of a vertical rib 11 and of a flange 12 at the upper edge of the rib. At the front end of lever 9 the thickness of this rib 11 is laterally enlarged in both directions, (see particularly Figs. 2 and 6,) permitting formation of two cheeks 13 13 with a recess 14 between, within and between which cheeks heel-piece D is pivotally supported, which being carried at the upper corner of the front end of the lever forms the actual contact-point with the car-wheel. This heel-piece consists of the angularly-arranged flange d with a rib below, which reaches into recess 14, where it is supported to have a limited pivotal motion, (note Figs. 1 and 2,) whereby slipping on the face of the car-wheel is prevented when the movement of the lever is started. The fulcrum A on which the lever swings is constituted by the pivot-pin shown thereat, the ends of which are supported in the sides 15 15 of a shoe, the base 16 of which rests on rail 17. From each lateral edge of this base there projects downwardly a lug 18, the object of which is to pre-

2
vent the implement from slipping off side-
wise from the rail while manipulated. To
5 prevent the shoe from slipping rearwardly
on the rail and away from wheel C when
power is applied at B, I provide a sole 19 be-
10 low base 16 of a material which does not
readily slip. Leather is the most preferable
material for this purpose, and the same is held
between two undercut or inwardly-beveled
15 ridges 21 on each edge of base 16. These
ridges also converge, so that a piece of leather
correspondingly cut may be pushed in be-
tween them and firmly held. Material
20 equivalent to leather for the purpose—like
rubber, fabric, or compositions of such ma-
terials—may be used in place of leather. A
customary steel spur 22, which is renewable,
25 may also be added. To increase the resis-
tance of the shoe against slipping, the larger
part of it, particularly of its base, is located
back of fulcrum A. To prevent the shoe
from sliding on the front edge of the leather
30 sole when the lever is pushed ahead, I pro-
vide a nose 23, which projects forwardly
from base 16 and which slides along the rail
as the implement is pushed forward.

Having described my invention, I claim as
new—

1. In a car-moving lever, the combination
30 with the lever proper, of an angular heel-
piece pivotally carried at the upper corner of
its front end and a shoe whereby the lever
rests upon the rail.

2. A car-moving lever, the front part of
35 which is T-shaped in profile and provided

with a vertical rib which is laterally enlarged
to form two cheeks with a recess between, in
combination with a heel-piece having an an-
gularly-arranged flange with a rib whereby it is
pivotally secured in the recess mentioned 40
and a shoe whereby the lever rests upon the
rail.

3. A car-moving lever, in combination
with a shoe on which it rests and which shoe
is provided with a contact-surface on its un-
der side, or sole of leather, or material equiv-
alent thereto like rubber, fabric or composi-
tions of these materials. 45

4. A car-moving lever in combination
with a shoe consisting of a base and two 50
sides projecting upwardly therefrom and be-
tween which it is fulcrumed and which base
is provided with ridges on its under side, one
on each edge, and a sole of leather held be-
tween these ridges. 55

5. A car-moving lever in combination with
a shoe consisting of a base and two sides
projecting upwardly therefrom and between
which it is fulcrumed and which base is pro-
vided with ridges on its under side, one on 60
each edge, a sole of leather held between
these ridges and a nose projecting from the
base in front of this sole.

In testimony whereof I hereunto affix my
signature in the presence of two witnesses. 65

GEORGE B. SULLIVAN
